UNITED STATES PATENT OFFICE.

MIGUEL ROSES ARTAU, OF SANTURCE, PORTO RICO.

HEAD COVERING.

Application filed August 13, 1924. Serial No. 731,826.

This invention relates to improvements in head covering.

The primary object of the invention is the provision of a head covering, which 5 may be a hat, cap, or crown portion therefore, embodying features which render the same particularly desirable for the cure of and for the prevention of baldness.

A further and important object of this 10 invention is the provision of a head covering which may be made of some translucent or transparent material, such as pyroxylin, and by means of which rays of light may have access to the hair of a person wearing 15 the head covering; it being also preferred to provide ventilating means for the improved head covering.

It is well known that the cause of baldness is occasioned, in cases where the baldness is not pathological, by reason of the 20 wearing of head coverings which do not permit sufficient circulation of air, and also because of other defects of conventional headwear. I have found that with the use 25 of a head covering, in which the crown, at least, is of ventilated and diaphanous material, the accumulation of carbonic acid is prevented, and the access of light to the hair and scalp excites the metabolic conditions 30 of the cells, giving to the roots of the hair the proper stimulation, and preventing baldness.

Other objects and advantages of this 35 invention will be apparent during the course of the following detailed description.

In the accompanying drawing, forming a 40 part of this specification, and wherein similar reference characters designate corresponding parts throughout the several views,

Figure 1 is a perspective view of a hat, showing the application of the improved feature to this hat.

Figure 2 is a cross sectional view taken 45 through the improved head covering.

In the drawing, wherein for the purpose 50 of illustration is shown only a preferred embodiment of this invention, the letter A may generally designate the head covering, which in the illustration shown is a hat, and consisting of an annular body portion B; brim C; and improved crown D.

In the illustration shown, the annular body portion B is entirely open at the top 55 thereof, and preferably has the brim flange C connected thereto at the lower edge por-

tion; the body B and brim C in the instance shown being of straw or analogous material. On the inner periphery of the annular body portion B it is preferred to provide a conventional sweat band 10, the upper edge of which terminates below the top edge of the annular portion B.

Referring to the improved crown D, the same includes the annular portion 20, and 60 the top wall 21, integral with the portion 20, and of the same material. It is preferred to provide this crown D of some transparent or translucent material, which may be of pyroxylin or analogous diaphanous material, to permit the entrance of 65 light therethrough, and this crown D may be tinted in any shade desired, or it may be transparent. It is preferred to provide an annular series of transverse perforations 70 75 23 in the annular portion 20, as is illustrated in Figures 1 and 2 of the drawing, for the purpose of ventilating the interior of the hat. As a neat means of connecting the crown portion D to the annular portion B it is preferred to provide an interior flange 24, extending inwardly of the crown portion 20 at right angles thereto, and provided with a depending attaching flange 25, which is inwardly of and concentric 80 85 with the annular portion 20, and which is adapted to overlie the inner periphery 27 of the hat portion B with the flange 24 resting upon the top edge of the portion B, as is illustrated in Figure 2 of the drawing, and in this position stitching 28 is sewed through the attaching flange 25 and the upper portion of the hat body B to attach the crown in the position shown.

It is preferred that with the assemblage of 90 95 the crown D upon the body portion B, the outer circumferences of the annular portions B and 20 will lie flush with each other, and a conventional hat band 30 may be annularly provided about the body portion B, slightly overlying the joint of the portions B and D to conceal the same.

From the foregoing description of this 100 105 invention it is apparent that when a person wears the hat, the daylight will be permitted to enter the pocket of the hat and reach the hair of the wearer. The annular series of openings 23 will afford ventilation and free circulation of air throughout the compartment of the hat, without disturbing the comfort of the wearer. While the crown D has been shown as assembled to a so called

body portion B of the hat, it is to be understood that the entire hat may be made of the diaphanous perforated material, and that the head covering may assume any form desired.

Various changes in the shape, size, and formation of parts may be made to the form of invention herein shown and described, without departing from the spirit of the invention or scope of the claim.

I claim:

In a head covering a body portion of substantially annular formation having a brim at the lower edge thereof, a crown of diaphanous material said crown including a top wall and an annular perforate side wall

portion adapted to lie flush with the outer surface of the annular body portion of the hat, said annular side wall portion of the crown having formed at the lower edge 20 thereof an inwardly extending flange adapted to rest upon the upper edge of the annular body portion of the hat and having a depending flange at the inner edge of the inwardly extending flange engaging the inner surface of the wall of the body portion of the hat, and a band of greater height than the outer wall face of the body portion for concealing the juncture of the body portion with the crown portion. 25

MIGUEL ROSES ARTAU.
